T. WICKERSHAM.
APPARATUS FOR PREPARING TEXTILE TREATING BATHS.
APPLICATION FILED NOV. 24, 1919.

Patented May 31, 1921.

UNITED STATES PATENT OFFICE.

THEODORE WICKERSHAM, OF PHILADELPHIA, PENNSYLVANIA.

APPARATUS FOR PREPARING TEXTILE-TREATING BATHS.

1,380,282.

Specification of Letters Patent. Patented May 31, 1921.

Application filed November 24, 1919. Serial No. 340,432.

To all whom it may concern:

Be it known that I, THEODORE WICKERSHAM, a citizen of the United States, residing in Philadelphia, Pennsylvania, have invented an Improved Apparatus for Preparing Textile-Treating Baths, of which the following is a specification.

My invention relates to the manufacture or preparation of silk threads from the raw material, and one object of my invention is to provide an improved bath in which the raw silk may be soaked preliminary to putting the same through the various operations necessary before the raw material may be spun into thread for subsequent use.

A further object of my invention is to provide an improved method or process of emulsifying liquids containing oleaginous material such as various combinations of oils whether such oils are of the same or different specific gravities.

My invention further includes apparatus in which this liquid bath or emulsion can be prepared, and the means employed in the preparation thereof in connection with the operation of said apparatus or any other form of apparatus in which such method or process involved in the preparation of the improved soaking bath forming part of my invention can be carried out.

These and other features of my invention are more fully described hereinafter, reference being had to the accompanying drawings, in which:

Figure 1 is a perspective view, partly broken away, of my improved emulsifying apparatus.

Fig. 2, is a sectional elevation, more or less diagrammatic, showing apparatus within the scope of my invention and in which my improved method or process of emulsifying liquids can be carried out.

The apparatus shown in the accompanying drawings and which I may employ includes a tank of heavy construction, indicated at 1 and shown in the drawings as resting upon the floor 2 of a building in which the work may be carried on. In this tank I propose to make a combination soaking bath for raw silk comprising soap, oil and water; such ingredients being incorporated or combined and emulsified under the influence of heat, with provision for circu-

lating the mixture through said tank until it is in proper condition for the desired purpose intended.

Within the tank 1 are mounted, preferably at the sides of the same, steam pipes or coils 2, receiving steam from a suitable source such as a boiler 4 not shown, such steam pipes or coils being provided with suitable return connections 5 for the water of condensation which may pass through a suitable trap (or traps) 6 and thence to the boiler.

Water from any suitable source may enter the tank via a pipe 7 having the usual controlling valve. Above the tank 1 I provide a soap boiler or other suitable receptacle 8 in which a soap solution of suitable character may be prepared; said receptacle having a pipe 10, suitably valved whereby the soap solution in any desired or suitable quantity may be delivered to the tank 1. In addition, I provide another tank 11 above the tank 1, for the reception of a prepared oil for use in the treatment of silk; the improved bath which I propose for treating raw silk comprising an emulsified body of a soap solution, water, and a prepared oil, in suitable proportions. The tank 11 is provided with a pipe 12 whereby the oil may be delivered to the tank 1.

It is highly desirable that the oil be delivered in measured quantities, and for this purpose the end of the tank is provided with a gage glass 13 graduated in inches and fractions of an inch, with a suitable index 14 whereby the volume of its contents may be read at a glance at all times.

After the desired quantities of water, soap and oil have been introduced into the tank 1, the mixture may be heated by forcing steam through the coils 2 within the tank, and this action may take place while the material is being emulsified. It is highly essential that this emulsifying action shall be complete, and for this purpose I propose to rapidly circulate the liquid through the tank and through the perforated pipes therein while the material is heated. For this purpose, the bottom of the tank is provided with a manifold, comprising a pipe 15 running longitudinally of the same, and having laterally extending branches 16 which with said pipe are perforated. The central portion of the manifold 16 is connected to a

pipe 17 leading to a suitable pump 18, preferably of the centrifugal type, and this pump receiving the liquid in course of preparation, discharges the same through a pipe 19, from which it may be delivered to the tank through pipe sections 20 and 21 connected to a pipe 22 disposed within the tank and having depending pipes 23. These latter pipes are perforated for the discharge of 10 the emulsified liquid raised by the pump.

As the quantity of liquid to be treated should economically be the same in preparing all batches of liquid, the tank is provided at the end with suitable gage glasses 25 15 graduated or having scales in inches and fractions thereof as well as suitable indicia at 26 so that the contents of the tank may be read at all times. The height of the tank is such that by preference two gage glasses 20 are employed.

When the mixture is completed, it is to be drawn off for use, and for this purpose the tank may be provided with a depending discharge pipe 28, having preferably at its 25 lower end a suitable nozzle 29 carried by a swiveled pipe 30 for convenient discharge into tank trucks or other suitable receptacles 31. The pipe 28 preferably has a valve 32 for controlling the discharge, and the discharge nozzle is preferably provided with a screen 33.

The tank may be provided with a cover 35, and the heating of the liquid may be under pressure or vacuum, as may be desired, 35 or the heating may be carried on at atmospheric pressure.

I claim:

1. In apparatus for preparing a treating bath, the combination of a tank, means for heating the same, liquid containers mounted above the tank and having discharge pipes 40 leading to the tank, a perforated pipe in the bottom of the tank for collection of the material contained therein, a perforated pipe in the top of the tank for the inlet of such material, a pump connected to said 45 pipes for drawing the material from the bottom of the tank and discharging it into the top of the same to insure proper circulation and emulsification thereof, and means for discharging the material from the 50 tank.

2. In an apparatus for preparing a silk-soaking bath, the combination of a tank, means for heating the same, soap and oil containers mounted above the tank and each 55 having a discharge pipe leading to the tank, a perforated pipe in the bottom of the tank for collection of the material contained therein, a perforated pipe in the top of the tank for the inlet of such material, a pump 60 connected in said pipes whereby the material may be drawn from the bottom of the tank and discharged into the top thereof to insure proper circulation and emulsification, a pipe for discharging the emulsified material from the tank, a pivoted discharge pipe connected to said pipe, and a screen 65 for said nozzle.

THEO. WICKERSHAM.
